UNITED STATES PATENT OFFICE.

JAMES M. COLEMAN AND KARL F. NYSTROM, OF MONTREAL, QUEBEC, CANADA.

DRAFT-ARM AND UNDERFRAME CONSTRUCTION FOR CARS.

1,279,989.

Specification of Letters Patent. Patented Sept. 24, 1918.

Application filed September 18, 1917. Serial No. 191,956.

To all whom it may concern:

Be it known that we, JAMES M. COLEMAN, a citizen of the United States, and KARL F. NYSTROM, a subject of the King of Sweden, both residents of the city of Montreal, in the Province of Quebec and Dominion of Canada, have invented certain new and useful Improvements in Draft-Arm and Underframe Construction for Cars, of which 10 the following is a full, clear, and exact description.

This invention relates to improvements in draft arms for freight cars, and the object of the invention is to provide a device applicable equally well to new constructions and as a repair to existing cars.

A further object is to provide a draft arm which extends continuously through the body bolsters of the car, so that the draft 20 arms at opposite ends of the car may be connected up to make a continuous rigid member from one end of the car to the other.

Wooden freight cars as constructed in the past were provided with a number of longitudinal frame timbers or sills to which the body bolsters were connected. Draft arms or draft timbers were then bolted underneath the longitudinal timbers extending from the ends of the car to the body bolsters. In a very short time, owing to the frequent sudden stresses of stopping and starting, and to the draft stress, these bolts and timbers became loose and the car was rendered unserviceable. Efforts were made 30 to repair the damage by inserting metallic draft arms which overlapped the longitudinal timbers and were bolted thereto. In order to secure a longer bearing, these metallic draft arms were offset so as to pass 35 above the body bolsters. To stiffen the car, metallic members forming center sills were frequently connected between the draft arms. At first sight, it would appear that such an arrangement would be satisfactory, 40 but in practice, it has been demonstrated that there is one very grave fault, namely, the offsets in this stiffening construction where it passes over the body bolsters. The draft line is below the longitudinal timbers 45 of a car, and therefore this offset carries the stiffening construction out of the draft line, so that considerable leverage is exerted on the draft arms where they are offset and fracture soon occurs.

50 From a consideration of these facts, we

have come to the conclusion that this difficulty may be overcome if a solid metallic construction is provided which extends through the body bolsters, so that the draft line will lie within the stiffening member 60 throughout the entire length of the car.

The structure expressing the conclusion mentioned in the foregoing paragraph in concrete form, comprises a pair of draft members at each end of a car, having flanges 65 to lie against and be bolted to the longitudinal timbers of the car, and depending portions suitably formed for the reception of the draft gear. This depending portion is cut away on each side of the body bolster, 70 so that the members are offset where they pass the bolster. A filler is provided which occupies the space between the compression and tension members of the bolster and connects at its ends with the depending portions of the draft members. This filler when in place is permanently connected to the draft member and body bolster in such a way that the member becomes continuous and rigid through the bolster and the line 80 of draft passes through this filler. When the draft arms at each end of a car are connected by metal beams, it will be readily seen that a member is formed extending continuously from end to end of the car 85 within which the line of draft is completely contained.

In the drawings which illustrate the invention:—

Figure 1 is a side elevation of a draft 90 arm.

Fig. 2 is a plan view of the same.

Fig. 3 is an end elevation.

Fig. 4 is a cross section on the line 4—4, 95 Fig. 2.

Fig. 5 is a side elevation of the underframe of a car showing the present invention applied thereto.

Referring more particularly to the drawings, 11 designates a pair of castings which 100 form the draft arm. These castings are exactly similar except that they are right and left hand, and each comprises a body portion 12 adapted to lie under the longitudinal members 13 of a car underframe, and a 105 flange 14 adapted to lie alongside and be secured to the longitudinal members 13 of the car underframe. Flanges 15 are connected to the body 12 and depend below the frame members 13. These latter flanges or 110

plates 15 are formed to receive the draft gear and project at their outer ends beyond the flanges 14 so as to form supports 16 for the end sill of a car. The outer ends of the flanges 14 may be provided with lateral projections 17 against which the inner surfaces of the end sills will abut. These projections may be provided with apertures 18 through which tension stays may pass for 10 secured to the end sills. A laterally projecting bracket 19 may be provided on each flange 14 over the body bolster 20, for the support of the stays. The depending part 15 of each draft member is formed with a 15 cut-away portion 21 extending some distance on each side of the body bolster. The body portion 12 is slightly offset where it passes over the bolster, as clearly shown in Fig. 1, and the adjacent ends of the plate 20 15 are suitably flanged as at 22.

A filler casting, designated 23, is provided to completely fill the cut-away portion of the plate 15 and to fit tightly between the upper and lower members of the bolster, and 25 against the offset portion of the body 12. This filler is provided with suitable flanges 24, by means of which it may be riveted to the flanges 22 of the plate 15, to the body 12 and upper member of the bolster, and to the 30 lower member of the bolster. This filler may be a separate member for each member 11, or may be a single member connecting the members 11, as shown. When the member 23 connects the members 11, it may be provided 35 in the space between the members 11 with a bearing 25 for the center pin, but when the member 23 is confined to a single draft member 11, the bearing for the center pin will be that which is already in the bolster. In any 40 case, the fillers 23 act as spacers between the tension and compression members of the bolster. The construction may be greatly strengthened by the addition of a plate 26 secured to the lower flanges of the plate 15 45 and to the lower flanges of the filler, so as to traverse the opening 21 in each draft member. The plate 26 may extend from one draft member to the other, as shown, or may be merely a narrow strip riveted to each individual draft member. The question as to 50 whether the filler 23 and plate 26 extend across the space between the draft members or not depends largely on the construction of the car to which the apparatus is applied.

55 The inner ends of the draft members may be provided with holes 27 through which rivets may pass to secure members 28 extending longitudinally of the car and connecting the draft members at opposite ends 60 thereof, as shown in Fig. 5. These members are preferably disposed symmetrically on opposite sides of the longitudinal center line in the well known manner, and may be of any suitable form, such as channels, I-beams, 65 plate girders or even pressed steel members

of the bath-tub type. The longitudinal stiffening members 28 may be entirely below the longitudinal timbers of the car under-frame, or if of the built-up type may have portions extending alongside of and secured to the timbers in the same manner as the draft arms. When these longitudinal members are in position, it will be obvious that the line of draft, designated 29, lies entirely within the continuous rigid metallic structure from end to end of the car.

In use, this continuous member from end to end of the car containing the line of draft is of great importance and a train made up of cars of this character may be likened to a string of beads. The string takes all the load and the individual beads have to support no more than the pressure applied to each. A train of cars built according to the construction outlined at the commencement of this specification may be likened to the same beads held together by being connected to one another without any continuous string. The straight line connection which results from this construction extending from end to end of a car or train is that best calculated to withstand tension and compression stresses, and relieves the car body and underframe of all these stresses. The solid filler in the offset portion of the draft members relieves the offset portion of all tendency to fracture under the application of either compression or tension stresses. The apparatus is inexpensive and may be easily and quickly inserted in existing cars, thereby greatly prolonging the life of wooden cars, and rendering them usable in trains made up of the larger and heavier metal or metal frame cars of more recent design.

It will be understood that the invention is not limited to the particular design of draft arm shown, as this may be varied as desired. In fact, the design of draft arm forms no part of the invention, except in so far as it is concerned with provision for inserting and securing the filler member, or its equivalent, which passes through the bolster. While the draft arm has been shown as extending beyond the bolster with an offset portion and a separate filler piece occupying the recess formed by the offset, it will be understood that in its broadest sense, the invention is not limited to this except by considerations of adaptability to existing car designs. Therefore, from at least a theoretical standpoint, the same result may be produced if the draft arm is formed in two pieces adapted to be secured together, and one of these parts has a portion which projects through the bolster and is the equivalent of the filler. It will also be understood that the use of a draft arm with a filler passing through the bolster is not limited to use with a longitudinal connecting member under the

central portion of the car, as the draft arms may be used without such a member. In either case, the extension of the draft arm through and past the bolster will give the 5 same distribution of stress.

Having thus described our invention, what we claim is:—

1. A draft arm comprising a pair of similar parts, each having a recess with offset 10 portions bridging said recesses, a filler in the recesses and extending from one part to the other, a bolster composed of upper and lower members between which the filler extends, said filler being connected to the parts 15 on opposite sides of the recesses, substantially as described.

2. A draft arm comprising a body recessed intermediate of its length, a bolster passing through said recess and composed of upper and lower portions, and a filler having laterally turned end flanges, the said draft arm having flanges extending vertically and laterally along the margins of the recess 25 and means for securing the flanges of the body and the filler together, said filler passing between the upper and lower portions of the bolster, substantially as described.

3. In combination, a draft arm having a recess intermediate of its length, a bolster comprising upper and lower members and a 30 filler in the recess and secured to the draft arm along its top and end portions, said filler having upper and lower recesses to receive

the upper and lower members of the bolster, substantially as described. 35

4. A draft arm composed of two parts, having upper vertical flanges and lower vertical webs spaced closer together than the upper flanges, with horizontal body portions extending inwardly from the upper vertical flanges to and connecting with the upper ends of the lower webs, each of said parts having a recess in its lower vertical web and reinforcements on the upper flanges above said recesses, a body bolster passing through the 40 recesses and filler means in the recesses secured to the lower vertical webs and engaging the said bolster substantially as described. 45

5. The combination with a bolster of a 50 draft arm, comprising a body, flanged plates depending therefrom in spaced relation and forming a passage for the bolster, a flanged filler inserted through the bolster having recesses therein for the reception of the 55 bolster members, and a member connecting said depending plates below the bolster and filler and secured to the bolster and filler, said filler being secured to the upper and lower bolster members, to the body of the 60 draft arm, and at its ends to the ends of the depending plates.

In witness whereof, we have hereunto set our hands.

JAMES M. COLEMAN.
KARL F. NYSTROM.
